US0D1043703S

(12) **United States Design Patent** (10) **Patent No.:** **US D1,043,703 S**
(45) **Date of Patent:** **** Sep. 24, 2024**

(54) **DISPLAY SCREEN OR PORTION THEREOF
WITH GRAPHICAL USER INTERFACE**

(71) Applicant: **Apple Inc.**, Cupertino, CA (US)

(72) Inventors: **Imran Chaudhri**, San Francisco, CA (US); **Jonathan Dascola**, San Francisco, CA (US); **Alan C. Dye**, San Francisco, CA (US); **Christopher Foss**, San Francisco, CA (US); **Jonathan P. Ive**, San Francisco, CA (US); **Stephen O. Lemay**, Palo Alto, CA (US); **Aled Williams**, Llandeilo (GB); **Christopher Wilson**, San Francisco, CA (US); **Eric Lance Wilson**, San Jose, CA (US); **Lawrence Yang**, San Francisco, CA (US)

(73) Assignee: **Apple Inc.**, Cupertino, CA (US)

(**) Term: **15 Years**

(21) Appl. No.: **29/779,175**

(22) Filed: **Apr. 16, 2021**

Related U.S. Application Data

(63) Continuation of application No. 29/682,102, filed on Mar. 1, 2019, now Pat. No. Des. 916,793, which is a (Continued)

CLAIM

The ornamental design for a display screen or portion thereof with graphical user interface, as shown and described.

DESCRIPTION

The FIGURE is a front view of a display screen or portion thereof with graphical user interface showing the claimed design.

The outer broken lines in the FIGURE show a display screen or portion thereof, and form no part of the claimed design. The other broken lines in the FIGURE show portions of the graphical user interface that form no part of the claimed design.

1 Claim, 1 Drawing Sheet

Related U.S. Application Data

continuation of application No. 29/628,147, filed on Dec. 1, 2017, now Pat. No. Des. 842,338, which is a continuation of application No. 29/600,155, filed on Apr. 10, 2017, now Pat. No. Des. 804,526, which is a continuation of application No. 29/572,564, filed on Jul. 28, 2016, now Pat. No. Des. 783,664, which is a continuation of application No. 29/519,762, filed on Mar. 6, 2015, now Pat. No. Des. 762,671.
